L. R. LEWIS

BINDER

Filed March 16, 1923.

Inventor:
Geo R. Lewis,
by Roberts, Roberts & Cashman,
Attys.

UNITED STATES PATENT OFFICE.

LEO R. LEWIS, OF SOMERVILLE, MASSACHUSETTS.

BINDER.

Application filed March 16, 1923. Serial No. 625,520.

To all whom it may concern:

Be it known that I, LEO R. LEWIS, a citizen of the United States of America, and resident of Somerville, in the county of Middlesex and State of Massachusetts, have invented new and useful Improvements in Binders, of which the following is a specification.

This invention relates to protective covers or binders for books, particularly for books of the kind which have flexible covers of paper such as magazines, periodicals, catalogues, sample books, pamphlets, briefs, reports, and the like.

Objects of the invention are to provide a simple, durable, efficient and inexpensive cover for temporary or permanent use which will give complete protection to the book therein enclosed without rendering inspection or use thereof difficult and without interfering in any way with the free action of the leaves.

The invention comprises a cover, preferably in the form of an integral sheet of a size to enclose the book, a stiff, solid filler, and means attaching the filler to the cover and the book to the filler. The cover and filler are preferably separable from each other and from the book. The thickness of the filler is preferably substantially that of the book to be covered, and for the purpose of adapting the cover or binder to books of different thicknesses the filler is preferably laminar and is built up of separate strips of suitable material such as wood or fibre board. The attachment of the filler to the cover is such as to permit the ready addition or removal of filler strips to make the thickness of the filler conform substantially to the thickness of the book to be protected, and the connection of the book to the filler preferably takes a form which permits the greatest freedom of action of the leaves and the book.

For the purpose of illustrating the invention certain embodiments thereof are shown in the accompanying drawings, in which:—

Fig. 1 is a plan view illustrating the binder in use, a portion of the cover being broken away;

Fig. 2 is a sectional view on an enlarged scale on the line 2—2 of Fig. 1; and

Figs. 3, 4 and 5 are partial sectional views similar to Fig. 2 showing modifications.

As illustrated, the invention comprises a cover A of tough paper or other suitable sheet material adapted to cover the sides

and back of a book. The cover is preferably integral and has folds at 6 and 7. Within the cover between the folds is a filler B attached to the cover sheet A in any suitable or desired manner, and attached to the filler B is the magazine or book C which is to be protected. It is desirable that the thickness of the filler B be made to conform substantially to the thickness of the book or magazine C, both on the score of the appearance of the assembled structure and its strength. If the book were materially thicker than the filler a strain would be thrown on the back of the binder especially along the folds 6 and 7 which might result in tearing. If the book were thinner than the filler an under strain would be thrown on the connection between the book and the filler, and the covers A would tend to bend inward and become deformed. Therefore, to make the filler variable in thickness, the filler is made laminar in form, being built up of juxtaposed strips b of suitable material such as wood, cardboard, fibre board or the like.

The means for attaching filler B to the cover sheet A is such as to permit easy addition or subtraction of filler strips. Such means may comprise straps 8 of suitable flexible material such as strong paper or binder's cloth passing through openings or slots 9 in the cover sheet at or near the folds 6 and 7 and extending over the back of the cover sheet between said openings, the free ends of the straps extending inside of the cover sheet and adjacent the top and bottom respectively of filler B. These strap ends and the strips b of filler B are provided with registering holes, through which pass suitable fastening means, preferably of a removable type such as a flat strip or ribbon of flexible metal 10, the body of which lies along one side of the filler B inside of cover sheet A, and the free ends of which pass through the aligned openings in straps 8 and strips b to be there bent over or clinched as at 11 on the opposite side of the filler. Any desired number of straps 8 may be used and more than one ribbon 10 or other fastener if desired depending upon the size of the book to be protected. One or both of the free ends of the straps 8 may be provided with a plurality of openings 12 for the fastener, or holes may be punched therein as needed when changing the thickness of filler B to adapt the binder to books of different thickness.

The book or magazine C is attached to filler B by one or more hinge members 13. These hinge members 13 may be formed of any tough flexible strip material, preferably cloth, and are preferably connected to the filler B or a portion thereof by a loop. In Figs. 1 and 2 the loop of the fabric hinge member 13 extends entirely around the filler B, the throat of the loop being stitched or otherwise fastened together at 14 adjacent the filler, and the free ends 15 being then made fast to the book C. One method of accomplishing this is to apply a coating of adhesive to the free ends 15 and sticking these ends to the outside of the binder sheet c of the book near its bound edge as shown in Figs. 2, 3 and 5. Inasmuch as a hinge member looped entirely about the filler B is adapted to a filler of only one uniform thickness, a modified form of attachment of the hinge strip is disclosed in Fig. 3 wherein the hinge strip 13' is looped around one of the filler strips b, preferably the middle strip as shown. This permits filler strips b to be added to or taken from the filler B without change in the attaching means for the book.

It is sometimes possible to secure a firmer anchorage or attachment of the book to the filler B by having the free ends of the hinge member 13 or 13' pass through the back of the book or magazine to the interior between two signatures, as shown at 15' (Fig. 3), said ends being gummed on the outer sides and attached inside the book by moistening them. Or these attaching ends might extend through a slot in the back of a signature instead of between signatures, especially in the case of a thin book. A further advantage of such inside attachment is that there is no interference with the later permanent binding of the book.

The invention is also applicable to the ring type of temporary binder. Such adaptation of the invention is disclosed in Fig. 5 wherein the strips b' forming the laminar filler B' are wedge shaped in cross section, or sectors of a circle whose center corresponds approximately to the center of the separable ring 17 which extends through openings 18 and 19 in strips b' and cover A' respectively, thus uniting the filler and the cover. The strips b' are all identical and may be added or removed as before, according to the thickness of the book. A flexible hinge member 20 similar to that disclosed in the other modifications is employed for attaching the magazine C to the filler B'. The loop of hinge member 20 may pass around all or any number of the strips b', and the attaching ends may extend between signatures as shown at 15, or be fastened to the outside of the book as in Fig. 2.

From the foregoing it will be seen that the binder may be quickly and easily ap-

plied to magazines and other books of widely varying thicknesses, and as easily removed by taking out the fastener 10, (or 17) whereupon the parts may be readily disassembled and all, save possibly the hinge member 13 which is stuck to the book, may be used again. The binder is light, compact and cheap. It adds little to the bulk of the book and does not interfere in the slightest degree with the full and free opening of the book and manipulation of the leaves, while at the same time affording a firm and solid support for the bound edge of the book and the back of the binder. The binder may be reversed inside out, or turned top for bottom or back for front. And the enclosed book or pamphlet may afterward be permanently bound or become part of a series in permanent binding. In the forms shown in Figs. 1 to 4, no metal or rigid part of any kind is exposed on the exterior of the binder; hence there can be no marring of tables or racks, nor any denting, nicking, scratching or tearing of books, magazines or papers which come in contact with the binder.

I claim:

1. A protective binder for books and the like comprising a flexible cover sheet folded to provide cover portions and a back, a filler between the cover portions of the sheet at a point adjacent to the back, means including a flexible part detachably connecting the filler to the back portion of the cover sheet, and flexible means for securing a book interposed between the cover portions of the cover sheet, to the filler.

2. A protective binder for books and the like comprising an integral cover sheet folded to provide cover members and a back member, a filler disposed between said cover members, means connecting the filler to the back member, said connecting means comprising a flexible element engaging said back member and a device detachably connecting the flexible element to the filler, and a flexible strap for uniting a book to the filler.

3. A protective binder for books and the like comprising a flexible cover sheet folded to provide cover members and a back member, a filler arranged between the cover members at a point adjacent to the back, a flexible strap having its central portion attached to the back member of the cover, means detachably securing the ends of the strap to the filler, and a flexible strap embracing the filler and adapted to connect a book thereto.

4. A protective cover or binder for books and the like comprising a cover sheet folded to cover the sides of a book, a filler within the fold of said sheet, a strap extending across the back of the binder with its free ends extending through spaced openings in said sheet to the inside of the binder, means

for attaching said free ends to the filler, and flexible means for attaching the book to said filler.

5. A protective cover or binder for books and the like comprising a cover sheet for embracing the book, a filler between the cover sheet and the back of the book, means extending through openings in the body of the sheet for attaching the filler to the sheet, said filler being laminar whereby the thickness thereof may be varied to conform approximately to the thickness of the book to be covered, and flexible means for attaching the book to said filler.

15 6. A protective cover or binder for books and the like comprising a cover sheet folded to cover the sides of a book, a filler within the fold of said sheet, means passing through spaced openings in the body of said sheet 20 for attaching the filler thereto, and flexible means for attaching the book to said filler, said filler being laminar to permit varying the thickness thereof to conform substantially to the thickness of the book to be covered.

25 7. A protective cover or binder for books and the like comprising a flexible cover sheet adapted to be folded to cover the book, a filler of superposed strips of relatively stiff 30 material adjacent the fold of said sheet, means passing through spaced openings in the body of said sheet to attach the filler to said sheet, and flexible means for attaching the book to said filler.

35 8. A protective cover or binder for books and the like comprising a cover sheet adapted to be folded to cover the book, a filler of superposed strips adjacent the fold of said sheet, means attaching said filler to 40 said sheet comprising a strap extending across the back of said sheet with its free ends extending through spaced openings therein adjacent the fold thereof, said strap being attached to said filler by means removably uniting the strips thereof, and flexible means for attaching the book to said filler.

45 9. A protective cover or binder for books and the like comprising a cover sheet, a 50 filler of superposed strips, means extending through openings in the body of said sheet for attaching said filler to said sheet including a member removably uniting said strips whereby the thickness of the filler may be varied to approximate the thickness of

the book to be protected by the removal or addition of one or more strips, and flexible means for attaching the book to the filler.

10. A protective cover or binder for books and the like comprising a cover sheet, a 60 filler adjustable in thickness secured to said sheet, and a flexible loop attached to said filler and adapted to be secured to a book.

11. A protective cover or binder for books and the like comprising a cover sheet folded 65 to protect both sides of a book, a filler adjustable in thickness within the fold of said sheet, straps extending across the back of the binder with their free ends extending through spaced openings in said sheet adjacent the fold thereof, means for attaching said free ends to the filler, and means for attaching a book to said filler.

12. A protective cover or binder for books and the like comprising a cover sheet, a filler 75 consisting of a plurality of superposed strips to permit variation of the filler in thickness to correspond substantially to the thickness of the book to be protected, straps passing through spaced openings in said cover, flexible means removably securing the free ends of said straps to said filler and uniting the strips thereof, and means for attaching the book to said filler.

13. A protective cover or binder for books 85 and the like comprising a cover sheet, a filler attached thereto composed of juxtaposed strips to permit varying the thickness of the filler to correspond substantially to the thickness of the book to be protected, and means 90 for attaching the book to said filler comprising a member secured to the book and looped around one or more strips of said filler.

14. A protective cover or binder for books and the like comprising a cover sheet folded 95 to cover the sides and back of the book, a filler within the fold of the cover sheet composed of a number of superposed strips, straps extending across the back of the cover sheet with their free ends extending through 100 spaced slots in said sheet to the inside thereof, fastening means for attaching said strap ends to the filler, and hinge members for attaching the book to the filler composed of flexible material connected to the filler by 105 a loop.

Signed by me at Boston, Massachusetts, this fifteenth day of March, 1923.

LEO R. LEWIS.
